United States Patent Office.

J. L. MARSH, OF RICHMOND, INDIANA.

Letters Patent No. 74,396, dated February 11, 1868.

IMPROVEMENT IN CHURN-DASHERS.

The Schedule referred to in these Letters Patent and making part of the same.

TO ALL WHOM IT MAY CONCERN:

Be it known that I, J. L. MARSH, of Richmond, in the county of Wayne, and State of Indiana, have invented a new and useful Improvement in Churn-Dashers; and I do hereby declare that the following is a full, clear, and exact description of the same, reference being had to the annexed drawings, making part of this specification, in which the dasher is shown in perspective.

This improvement is intended for application to that class of churn-dashers which, revolving with a rotating shaft, bring projecting arms into action upon the cream.

The following description will enable persons skilled in the art to construct and apply to use my improved churn-dasher.

In the annexed drawings, A is the rotating shaft, which may receive motion from a bevel-wheel driving the pinion B, or in any other convenient manner. Arms, C, project from the shaft on each side. The teeth D are inserted in the arms to still further break up the globules of cream. To these teeth I attach conical blocks, E, by means of cords E'. As the shaft revolves, and with it the arms C and teeth D, these blocks will be drawn through the cream, causing a violent agitation thereof, which will materially assist in breaking up the globules and hastening the formation of butter.

What I claim as my invention, and desire to secure by Letters Patent, is—

A rotary churn-dasher, constructed with the shaft A, arms C, teeth D, and blocks E, attached thereto by cords E', said parts being arranged to operate substantially as described.

In testimony whereof, I have signed my name to this specification in the presence of two subscribing witnesses.

J. L. MARSH.
